DESIGN FOR A CLOTHESPIN

Louise M. G. Olivier, Hull, Quebec, Canada

Application July 10, 1945, Serial No. 120,622

Term of patent 14 years

(Cl. D17—6)

To all whom it may concern:

Be it known that I, Louise M. G. Olivier, a citizen of the Dominion of Canada, residing at Hull, in the county of Hull, in the Province of Quebec, Dominion of Canada, have invented a new, original, and ornamental Design for a Clothespin, of which the following is a specification, reference being had to the accompanying drawing, forming a part thereof.

The figure in the drawing is a perspective view of the clothespin, showing my new design.

I claim:

The ornamental design for a clothespin, as shown.

LOUISE M. G. OLIVIER.
